UNITED STATES PATENT OFFICE.

CHARLES A. STENIUS, OF SOUTH BEND, INDIANA.

SERVING DEVICE.

1,002,331.

Specification of Letters Patent.

Patented Sept. 5, 1911.

Application filed August 29, 1910. Serial No. 579,533.

To all whom it may concern:

Be it known that I, CHARLES A. STENIUS, a citizen of the United States, residing at South Bend, in the county of St. Joseph and State of Indiana, have invented certain new and useful Improvements in Serving Devices, of which the following is a specification.

My invention relates to improvements in devices for serving meals, and has for its object the provision of means whereby meals may be delivered to a distance, as to private apartments in a hotel, or to destinations without the place where the cooking is done, and served substantially as hot as when first dished for delivery.

A further object of the invention resides in the provision of a serving device which permits ready access to be had thereto, so that the contents need not be removed therefrom, and the meal partaken of without handling of the dishes.

A still further object of the invention resides in the provision of means whereby the device may be easily and quickly disassembled, so that parts which would otherwise be inaccessible will be exposed for cleansing purposes, and thus permit the device as a whole to be kept in a perfectly sanitary condition.

With these and other objects in view, the invention consists of certain novel features of construction, as hereinafter described and pointed out in the claims.

In the drawings employed for illustrating the preferred embodiment of the invention:—Figure 1 is a sectional plan view taken on a line $x-x$ of Fig. 2, the revoluble tray portion being broken away to more clearly show parts located beneath the same. Fig. 2 is a vertical sectional view taken on a line $y-y$ of Fig. 1. Fig. 3 is a fragmentary sectional view showing the location and interrelation of the various parts. Fig. 4 is a perspective view of one of the posts comprised in the frame-work of the device. Fig. 5 is a fragmentary view showing the upper edges of the post, side wall and sliding door. Fig. 6 is a top view of the complete device, with detachable shelves mounted thereon. Fig. 7 is a fragmentary side view of the device with a shelf attached thereto. Fig. 8 is an end view of one of the shelves.

The frame-work of the device preferably comprises a base which consists of a central

portion 1, which has a socket 2 in its upper face of conical formation, the object of which will be presently explained. Extending radially from the central portion are 60 arms 3, which are irregular in formation so as to provide stub legs 4, and recesses 5, in order to provide a clearance for roller bearings 6, which may be mounted upon the arms in any suitable manner. A recess is 65 formed in the arms near the ends thereof, as at 7, and the ends of the arms extend upwardly so that the upper sides thereof will be slightly higher than the remaining portion. A transverse groove 8 is formed in 70 the upper face of the arms near their ends, and a like groove 9 adjoining the upper outer edge of the recesses 7. An annular rim 10, of sheet metal, having an outer turned edge 11, to add rigidity thereto, and 75 a groove 12, the formation of which provides a bead on the lower side of the rim, is disposed upon the base arms with said turned edge and bead engaging the grooves 8 and 9 in the arms. The inner portion of 80 the rim is formed so as to conform in cross-section with the contour of the recesses in the arms, as plainly shown in Fig. 3, and thus provides an annular trough 13, to catch all liquid foods which may be accidentally spilled within the device. Mounted at the end of each arm is a post 14, which is disposed on top of the rim 10, after the latter is in the proper position, and secured in place by bolts 15, passed through the base of 85 the post and through strengthening plates (not shown) secured to the under side of the rim adjacent the base arms.

The post members 14, comprise an upright portion having a longitudinal groove 16 95 formed in one of the side edges thereof, the alternate posts having the grooves formed in the opposite edges, so as to receive the opposite ends of the side wall members 17, and with the laterally extending ears 18, 100 serve to detachably hold the said side wall members, which are arc-shaped and preferably of sheet metal, in the proper position. The upper ends of the posts are off-set and provided with rounded grooves 19, 20 and 105 21, in their sides and top, the object of which will be presently explained. The references 22 and 23 represent arc-shaped sliding doors, each composed of two sections which are arranged to slide in opposite directions, and 110 the lower edges of which engage the annular groove 9 in the rim, which groove serves

as a track for the door sections to slide in, and also to prevent lateral displacement thereof. Each of the door sections have their opposite end edges 24 bent outwardly 5 to form stops for contact with the sides of the posts, so as to effect a tight closure between said members at that point, the bent portions being notched, as at 25, so as to pass the ears 18 without interference. One 10 of the adjoining end edges of the door sections is off-set, so as to lap over the other section, and each section is bent outwardly and upwardly at its upper edge 25', so as to extend over the shoulders 26 of the posts. 15 In order to complete the upper portion of the side wall structure, and to provide a guideway for the upper edges of the sliding doors, I employ an annular member 27, which is right-angled in cross section, and 20 each arm of which has a bead 28 and 29, which engage the grooves 20 and 21, respectively, in the posts, the lower edge of the vertical arm meeting the upper edges of the side wall members, and the upper 25 edges of the sliding doors extending above the lower edge of the vertical arm. The engagement of the beads with the grooves locks the annular member in position, and being of sheet metal and yielding, the same 30 may be easily sprung into position or detached at will. The same also adds rigidity to the whole structure, as the vertical arm prevents inward movement of the upper ends of the posts. 35 An annular crown member 30, which is substantially of inverted U-shaped formation in cross-section, and having beads 31 and 32 formed on its edges, is disposed so as to rest upon the upper side of the annular member 27, the outer arm 33 extending downwardly and its beaded edge engaging the grooves 19 in the posts, and its inner arm 34 extending downwardly in spaced relation with the vertical arm of the member 27, to form a guideway for the upper edges of the sliding doors. The crown member being of sheet metal and slightly yielding, is also easily sprung into position, the bead on the outer arm holding the same 40 against accidental displacement, while at the same time permitting the crown member to be easily and quickly detached. A cover or lid 35, having an annular flange 36, and a knob handle 37, permits ready access 45 to be had to the interior of the device, for placing or removing dishes therefrom. The bottom or tray 38, is in the form of a circular disk, and has a cone shaped pivot pin 39 on its under side, which pin engages the 50 cone shaped socket 2, formed in the upper side of the base, which pin serves as an axis for the tray, to hold same in the proper position and permit it to be revolved. The tray rests upon the roller bearings, which 55 support and permit the same to be easily

revolved when heavily loaded, and enables the party served to easily help himself without removing the dishes from the tray, as by sliding open the doors on the side the contents will be in full view, and by revolving the tray any part thereof may be brought directly within reach. The device is provided with a double set of doors, so that either one or two parties may be served at the same time. 75

I have thus provided a serving device or tray which is completely inclosed, so that the heat and steam arising from the food will be confined and prevent the rapid cooling of the food, whereby meals may be delivered hot at a considerable distance from the kitchen, and held in a warm condition in a cold atmosphere for a considerable period of time. 80

It will also be observed from the foregoing description, that the device may be easily and quickly disassembled, so as to render all parts accessible for cleansing purposes, and enable the same to be kept in a perfect sanitary condition. 85

The revoluble tray may be locked against movement in any suitable manner, as by mounting a lock on the under side of the tray and having a bolt arranged to engage apertures arranged in the adjoining rim, the 90 position of the lock being indicated at 40. As the manner of locking the tray may be accomplished in many ways and with various styles of locks, and as no specific form of locking mechanism is claimed herein, it is 100 not deemed necessary to illustrate and describe the same in detail.

In order to increase the capacity of the device, I provide same with detachable brackets 41, having pins 42 at their opposite ends adapted to engage socket members 43, secured to the posts, bracket arms 44 carried by the brackets extending downwardly at an angle and terminating in a head 45 having a socket therein, for engagement with the fixed pins 46. The brackets may thus be easily removed when not required, and as they are disposed so as to adjoin the side wall members, they do not interfere with or block the side door openings. 110

Having thus described my invention, what is claimed is:—

1. In a portable serving device, the combination with the base, of a rim member mounted thereon comprising a trough portion, a tray mounted on the base having its edge extending over said trough and spaced from the wall thereof, and a hood for the tray. 120

2. In a portable serving device, the combination with a base comprising radially extending arms, of an annular rim member mounted upon the outer ends of said arms and having a trough formed around its inner edge, a circular tray mounted for rotation 130

upon the base and having its edge extending over said trough, and a hood for the tray.

3. In a portable serving device, the combination with the base, of a tray mounted thereon, a hood comprising a plurality of posts, segmental side-wall members detachably engaging said posts, sliding side-door sections, annular detachable frame members engaging grooves in the upper ends of said 10 posts and having downwardly extending relatively spaced flanges to form a guideway for said door sections, and a removable lid for the hood.

4. In a portable serving device, the combination with the tray, of a hood comprising a plurality of posts, sectional side-wall members detachably engaging said posts, sliding side-door sections, frame members adapted to be sprung into and detachably held in 20 engagement with the upper ends of said posts and relatively spaced at their inner

edges to form a guideway for the side-door sections.

5. In a serving device, the combination with the base, of an annular rim member 25 mounted thereon and embodying a grooved guideway and trough, a tray mounted on the base and extending over said trough portion, a hood comprising a plurality of posts, means on the posts for detachably holding 30 segmental side wall members, detachable frame members connecting the upper ends of the posts and spaced on one side to form a guideway, sliding side door sections arranged to slide in said guideways, and a lid 35 for the hood.

In testimony whereof I affix my signature, in presence of two witnesses.

CHARLES A. STENIUS.
